ELECTRICAL TELEINDICATING DEVICE

Nicolas Emilian Methlin, Paris, France, assignor
to Schneider & Cie., Paris, France, a company
of France

Application November 25, 1932, Serial No. 644,366
In France December 19, 1931

6 Claims. (Cl. 177—351)

The present invention relates to a device for controlling at a distance any movable elements with a view to bringing them into a well-determined position.

5 The particular feature of the invention is that it renders possible the transmission of an algebraic sum of distinct indications provided by a plurality of independent mechanical devices installed at the transmitting station.

10 The invention is more particularly applicable for controlling gun-fire.

The accompanying drawing shows diagrammatically by way of example the manner in which the invention may be applied for transmitting the indication of the future azimuth of an objective to the servers of a gun employed for firing against aerial objectives, the said indication being obtained by performing the algebraic sum of the actual azimuth, as determined by a direct sight, and of the kinetic correction allowing for the displacement of the said objective during the flight of the projectile, it being known that this correction may be determined as a function of the voltage furnished by a small magneto-electric machine driven by the aiming mechanism.

In the diagram, in which T is the transmitter and R is the receiver, 1 denotes a shaft driven by the rotatable member an indication of the position of which it is desired to transmit to the receiver—in a fire control system, 1 might be rotated in accordance with the movements in azimuth of a target sighting mechanism; 2 is a potentiometer curved in a circle having its centre at 3; 4 is a diametral brush holder keyed to 1 and thus adapted to rotate about 3, driving the two brushes 5 and 6 which wipe over 2 in two points situated at the ends of one and the same diameter; 7 and 8 are two current collecting rings integral with the brush holder and connected respectively to 5 and 6. These rings are wiped by two fixed brushes 9 and 10 connected respectively to the fixed contacts 11 and 12 of a two-way switch 13 having its movable arm 14 influenced by a spring 15 and adapted to be attracted by an electro-magnet 16. The reference characters 1', 2', 3' . . . 16' respectively denote elements corresponding to 1, 2, . . . 16 but situated at the receiving station R. Shaft 1' is adapted to be rotated manually by the receiving station operator to such position that it corresponds with the position of shaft 1 at the transmitting station. In a fire control system, 1' might be actuated in accordance with the training movements of a gun in azimuth.

At 17 is indicated a source of direct current feeding the potentiometers 2 and 2'. A rotary switch 18 is mounted on 1 and is utilized for maintaining the electro-magnets 16 and 16' energized as long as the brush 5 is on the upper half of the potentiometer 2. When brush 5 passes onto the lower half of potentiometer 2, rotary switch 18 de-energizes electro-magnets 16 and 16' and springs 15 and 15' move switch arms 14 and 14' into engagement with contacts 10 12 and 12', thereby connecting brush 6, which is then on the upper half of potentiometer 2, and brush 6' to the control wire circuit next to be described. With this construction, the upper halves of the potentiometers are always the controlling portions, thereby avoiding the possibility of erroneous operation of the indicating system should a brush holder stop in such position that one of its brushes lies in the gap between the ends of the potentiometer coil.

20 A voltmeter 19, located at the receiving station and constructed to indicate simultaneously the direction and magnitude of the current passing through it, is connected between 14 and 14' by means of a control wire 20. A source of direct current 21 is connected in series with 20 and may be suitably constructed and controlled so that its voltage is proportional to the correction which is to be added algebraically to the indication of the actual position of shaft 1 and brush 30 holder 4. In a fire control system, element 21 may comprise a suitable magneto-electric machine which is so connected with the target observing mechanism that the voltage generated thereby is a function of the kinetic correction to 35 be applied to the actual azimuth of the target at any instant to take care of the azimuthal displacement thereof during the time of flight of a projectile fired from receiving station R. As one example of such a magneto-electric machine, reference may be had to U. S. Letters Patent No. 1,345,700 to Routin, granted July 6, 1920. At 22 is indicated a source of alternating current connected in series with 20, and its usefulness will be explained hereinafter.

40 It will be seen in the first place that the switches 13 and 13', being controlled by 18 as stated hereinbefore, the two groups of brushes 5—5' and 6—6' are automatically put into service alternately, and consequently, if 21 and 22 45 provide voltages of zero value, everything will take place as if there were employed two transmissions by Wheatstone bridge of known type (for example, as disclosed in French Patent No. 508,952, of the 21st December 1917), utilized al- 50 55

ternately. In other words, if elements 21 and 22 are so adjusted or operated as to impress no additional voltage on control wire 20, the circuit operates as an ordinary Wheatstone bridge with control wire 20 and voltmeter 19 constituting the bridge circuit; and by moving shaft 1' and its associated brush holder 4' until voltmeter 19 registers zero, the position of shaft 1 may be indicated or reproduced at the receiving station by the position of shaft 1'. In a fire control system, this would result in the gun or other mechanism associated with shaft 1' being moved to the same azimuth as the mechanism associated with shaft 1.

15 It will also be appreciated that if the voltage provided at 21 is denoted by e , it will be necessary, in order to return the pointer of voltmeter 19 opposite its zero mark, to displace shaft 1' and brush holder 4' relatively to shaft 1 and 20 brush holder 4 through an angle (positive or negative) proportional to e . Thus, in a fire control system, a correction due to movement of the target during the time of flight may be superposed upon and algebraically combined with 25 the indication of the actual azimuth at any instant as determined by the position of shaft 1', the result being that when the electrical circuit is properly balanced to give a zero indication on voltmeter 19, the position of shaft 1' indicates 30 the true azimuth of the target corrected for its expected movement during the time of flight.

Finally, it will be observed that by suitably adjusting the frequency and the voltage of 22, the pointer of 19 may be given a vibration of 35 very slight amplitude which, without causing any interference in the operation of the distant indication, possesses the considerable advantage of providing an automatic check on the condition of the lines and on the working of the apparatus. 40 It is, in fact, obvious that any vibration of the pointer would disappear if, for example, the circuit through connecting wire 20 were broken, or again if the brush 5' were brought into the zone of interruption separating the two ends of 2', 45 the transmitter being in the position shown in the figure.

In the case of a plurality of receivers, a distributor may be mounted on 20 in known manner (see for example the French Certificate of Addition No. 23623/508952 of the 3rd March, 1920 and the U. S. Letters Patent No. 1,471,708).

While, by way of exemplification, the present invention has been described as it might be applied to a fire control system, it will be expressly 55 understood that it is not limited to such use, but is capable of employment in any suitable tele-indicating device wherein it is desired to bring a mechanically movable element at one station to a position corresponding to that of a similar element at a distant station, either with or without a correction to the position of the former which is independently introduced into the system by still another movable element. It is also 60 to be understood that the specific form and construction of the magneto-electric machine 21 and alternating current source 22 form no part of the present invention, any suitable mechanisms of the character described being within the contemplated scope of the invention. Various other 65 changes which will now appear to those skilled in the art may be made in the form, details of construction and arrangement of the parts without departing from the spirit of the invention, and 70 reference is therefore to be had to the appended

claims for a definition of the limits of the invention.

Where, in the specification and claims, reference is made to the "upper" half of potentiometers 2 and 2', it will be understood that this term is used in a relative sense only to designate that semi-circumferential portion of each potentiometer which is symmetrically located between the terminals thereof. Likewise, the "lower" half of each rheostat is meant to indicate the 10 half in which the terminals are centrally located.

I claim:

1. In an electrical tele-indicating device of the type employing a circular rheostat at each of the transmitting and receiving stations, a contact carrying arm rotatably associated with each of said rheostats, a source of potential connected across the terminals of each of said rheostats, and a bridge circuit connecting said transmitting and receiving stations including an electrical device responsive to the flow of current in said circuit, the combination of a pair of contacts carried by each of said arms and engaging the associated rheostat at diametrically opposite points, and means controlled by the position of the arm at the transmitting station for connecting the bridge circuit to that contact of each of said pairs which at any instant is in engagement with that half of its associated rheostat which is symmetrically disposed between the terminals thereof. 30

2. In an electrical tele-indicating device of the type employing a circular rheostat at each of the transmitting and receiving stations, a rotatable contact carrying arm associated with each of said rheostats, a source of potential connected across the terminals of each of said rheostats and a bridge circuit connecting said transmitting and receiving stations including an electrical device responsive to the flow of current in said circuit, the combination of a pair of diametrically opposite contacts carried by each of said arms and engaging the associated rheostat, and electromagnetic means controlled by the position of the arm at the transmitting station for connecting the bridge circuit to that contact of each of said pairs which at any instant is in engagement with that half of its associated rheostat which is symmetrically disposed between the terminals thereof. 45

3. In an electrical tele-indicating device of the type employing a circular rheostat at each of the transmitting and receiving stations, a contact carrying arm rotatably associated with each of said rheostats, a source of potential connected across the terminals of each of said rheostats, and a bridge circuit connecting said transmitting and receiving stations including an electrical device responsive to the flow of current in said circuit, the combination of a pair of contacts carried by each of said arms and engaging the associated rheostat at diametrically opposite positions, a pair of fixed terminals electrically connected with each of said pairs of contacts, a switch arm connected to each end of said bridge circuit and adapted to contact one or the other of the pair of fixed terminals at the respective station, and means controlled by the position of the contact carrying arm at the transmitting station for moving each of said switch arms into contact with that fixed terminal of each of said pairs which is electrically connected to that contact which at any instant is in engagement with the upper half of its associated rheostat. 65

4. In an electrical tele-indicating device of the type employing a circular rheostat at each of the 75

- transmitting and receiving stations, a rotatable contact carrying arm associated with each of said rheostats, a source of potential connected across the terminals of each of said rheostats and 5 a bridge circuit connecting said transmitting and receiving stations including an electrical device responsive to the flow of current in said circuit, the combination of a pair of diametrically opposite contacts carried by each of said arms and 10 engaging the associated rheostat, a pair of fixed terminals electrically connected with each of said pairs of contacts, a switch arm connected to each end of said bridge circuit and adapted to contact one or the other of the pair of fixed terminals at the respective station, means yieldably urging each of said switch arms into contact with one of its associated pair of fixed terminals, an electromagnet associated with each of said switch arms and 15 adapted to move each of said arms into contact with the other of its associated pair of fixed terminals, means including a rotary switch operated by the contact carrying arm at the transmitting station for energizing said electromagnets only when the contact at the transmitting station electrically connected to the last mentioned fixed terminal is in engagement with the upper half of 15 the circular rheostat at the transmitting station.
6. An electrical signalling system of the type employing a circular rheostat at each of the transmitting and receiving stations, a movable contact carrying arm associated with each of 20 said rheostats, a source of potential connected across the resistance elements of said rheostats arranged in parallel, and a single bridge wire including a voltmeter connecting said transmitting and receiving stations, characterized by 25 the provision in combination of a pair of contacts carried by each of said arms and engaging the associated rheostat resistance elements at diametrically opposite points on their circumferences, and means operated by the arm at the 30 transmitting station for connecting the bridge wire to that contact of the transmitting pair of contacts which at any instant is operating on the semi-circumference of the resistance element 35 symmetrically opposite the ends of the said resistance elements, and to the corresponding contact of the receiving pair of contacts.
